UNITED STATES PATENT OFFICE.

CHARLES O. VIERS AND LOVELL D. SHELDON, OF TOLEDO, OHIO.

DOOR MOUNTING.

Application filed June 23, 1926. Serial No. 117,956.

This invention relates to door mountings, but more particularly to mountings which permit the door to be moved clear of the opening when not in use, such mountings being especially useful for refrigerator cars where a tight closure is highly desirable for insulating the inside of the car from the outside, and where a free and unobstructed opening for discharging the contents of the car is wished.

Objects of this invention are to provide a novel and efficient door mounting which permits the door to be moved entirely clear of the door opening when not in use and which eliminates the use of hinges between the door and side of the door opening; to provide a mounting for a door in which opposite sides of the door are movably connected to a frame in such a manner that the door may be moved straight out from the opening or into registration therewith; and to provide a mounting having the new and improved features of construction and arrangement hereinafter described.

The invention is shown by way of illustration in the accompanying drawings, in which:

Fig. 1 is a side elevation of the door mounting showing the door in closed position; Fig. 2 is a view similar to Fig. 1 showing the door removed from the opening and disposed at one side; Fig. 3 is a section on the line 3—3 of Fig. 1; Fig. 4 is a section on the line 4—4 of Fig. 2; Fig. 5 is a section on the line 5—5 of Fig. 3; and Fig. 6 is a section on the line 6—6 of Fig. 4.

The illustrated embodiment of the invention comprises a refrigerator car 1 which is provided with a door opening 2 which is tapered inwardly from the outside, and into which fits a door 3, the sides of the door being correspondingly shaped to fit tightly within the opening 2, as indicated in Fig. 3. The door 3 may be provided with any suitable handle 4 and is carried by a rectangular frame or mounting 5 which carries on the inner side thereof, grooved rollers 6 disposed at the several corners, and which engage tracks 7 spaced outwardly from and carried by the side of the refrigerator car 1.

The door 3 may be provided with suitable locking means, and in this instance, rack bars 8 and 9 are slidable in the door and may be actuated by a pinion 10 which

is formed in a squared opening 11 to receive a suitable tool for turning the pinion. As shown in Fig. 1, the rack bars 8 and 9 may be extended in opposite directions into sockets 12 and 13 respectively, in the top and bottom-sides of the opening 2. When the door 3 is moved away from the opening 2 into a plane substantially coincident with the plane of the frame 5, the rack bars may be extended into socket members 14, which are carried on the upper and lower cross bars of the frame.

The door 3 is connected to the frame or mounting 5 in such a manner that it may be pulled straight out from the opening 2 so as to be completely separated therefrom. This movement is such that the sides of the door 3 are concomitantly separated or removed from the edges of the opening 2. It will be seen that swinging movement of the door is eliminated, such movement being necessary if the door were attached to the side of the car by means of the ordinary hinges. Furthermore, by this arrangement, the door may fit snugly and seal the inside of the car so that this arrangement is particularly useful in the case of a refrigerator car where it is desired to insulate the inside of the car from the outside atmosphere.

As shown, the opposed sides of the door 3 are connected to the frame 5, and in this instance, four hinge members being employed, although it will be understood that the number and arrangement of these hinge members may be varied, as desired, and according to the needs of service. Each hinge member comprises a pair of plates 15 and 16 which are secured respectively to the door 3 and frame 5. These plates are connected together by links 17, 18, and 19, the link 17 being pivotally connected at one end to the plate 15, and at the other end to the link 18, which in turn is connected at its opposed end to the link 19, the link 19 being connected to the plate 16. As shown, the various links interfit so that lateral movement of the links with respect to each other is prevented. As shown in Fig. 5, when the door 3 is closed the links are disposed in extended position, but when the door 3 is withdrawn from the opening 2, the links are disposed in the position indicated in Fig. 6, thus permitting the door to be drawn straight out from the opening 2. It is to be understood that the operation of

the other hinge members is similar to that above described, so that description of but one member is deemed sufficient.

In use, the frame 5 is moved into such position that the door 3 is directly over the opening 2. Thereafter, the locking members 8 and 9 are retracted from the socket members 14, and the door 3 may be moved straight inwardly into registration with the door opening 2. By again manipulating the locking mechanism the locking bars 8 and 9 may be extended into the sockets 12 and 13, respectively, so that the door is securely locked in place. It will be apparent that by this construction the inside of the car is effectively sealed and removal of the door is prevented without the use of a tool suitable to operate the locking device.

When access to the interior of the car is desired, the locking members 8 and 9 may be retracted from the sockets 12 and 13, thereby permitting the door to be moved straight outwardly, and after being properly positioned with respect to the frame 5, the locking members 8 and 9 may be extended into the respective socket members 14, so that the door is held in proper relation to the frame 5. The frame 5 may be then rolled away from the opening 2, and any suitable catch, such as an arm 20 on the frame having a notch 21 to engage a pin 22 on one of the rails 7 may be provided to hold the frame in the desired position away from the opening 2. In this manner the opening 2 remains completely unobstructed, and removal of the contents of the car may be effected without interference.

Heretofore in refrigerator cars, two doors have been utilized, each being hingedly connected to the adjacent structure of the car and, when closed form a tight seal. While these doors accomplish their purpose in effecting a seal, nevertheless, they have been found dangerous in that when the doors are open, persons are frequently injured by passing trains. Furthermore, should a door of these refrigerator cars be swung open, it would be impossible to approach the loading

platform, because the doors in their open position extend a considerable distance from the side of the car. It will, therefore, be seen that our arrangement unmistakably overcomes the objections above noted and provides a construction which eliminates the liability of injury to persons as well as providing an extremely useful and efficient device. It is particularly to be noted that when opened our door only occupies but a half inch more than the thickness of the door.

While we have shown and described a construction which is the best form known to us at the present time, it is to be understood that numerous changes in details of construction and arrangement may be effected without departing from the spirit of the invention, especially as defined in the appended claim.

What we claim as new and desire to secure by Letters Patent is:

A hinge for connecting a door to a support spaced from and parallel to the door opening for movement of the door in a plane parallel to the plane of the door opening and the support, composed of a pair of oppositely disposed plates, one of which is formed to be connected to the outer face of a side of the door and to extend beyond the said side of the door, and the other of which plates is formed to be secured to the inner face of the adjacent side of the support and to project beyond said side of the support and toward the first named plate, and links pivotally connecting the said projecting inner ends of the plates, said links being formed so as to lie in substantially the plane of and between the said side of the door and that of the support in open position of the door, and to extend across the space between the door and its support in closed position of the door.

In testimony whereof we have hereunto signed our names to this specification.

CHARLES O. VIERS.
LOVELL D. SHELDON
